UNITED STATES PATENT OFFICE.

ROBERT ERNEST ATKINSON, OF KNIGHTON, ENGLAND.

STEAM-HEATING SYSTEM.

No. 920,244.

Specification of Letters Patent.

Patented May 4, 1909.

Application filed May 17, 1907. Serial No. 374,299.

To all whom it may concern:

Be it known that I, ROBERT ERNEST ATKINSON, a subject of the King of Great Britain and Ireland, and residing at Morland avenue, Knighton, Leicester, England, engineer, have invented certain new and useful Improvements in Steam-Heating Systems, of which the following is a specification.

This invention relates to steam-heating systems, and more particularly to systems employing piping which is divided into two passages, one for flow and one for return, the object of the invention being to enable piping of this type to be efficiently employed in a steam-heating system provided with automatic controlling valves upon the radiators, and to insure that the return water of condensation can be effectively led away and, further, to facilitate the connection of the individual length of piping at different positions without interfering with the flow and return and in such a manner that all the fittings or connections to the radiators or heaters can be arranged upon one side of each apparatus, the point of connection upon each radiator or the like serving both as the inlet and outlet.

Referring to the accompanying drawings: Figure 1 is a diagrammatic elevation illustrating a portion of a steam-heating system according to the invention, Fig. 2 being a sectional elevation on the line A—B (Fig. 1); Fig. 3 is a sectional plan on the line C—D (Fig. 1); Fig. 4 is a sectional elevation of an automatic controlling valve, Fig. 5 being a cross sectional end view of the connecting branch thereof, taken on the line E—E (Fig. 4). Fig. 6 illustrates in two sectional views a packing plug or gland, employed in the regulator shown in Fig. 4.

In carrying out the invention according to one mode—as illustrated, for example, in the accompanying drawings—steam from a boiler situated in any part of a building or elsewhere is conducted by an ordinary single steam main, *a*, which, by means of a connection, *b*, of the form comprising two passages or chambers, *c* and *d*, is connected to a T-piece, *e*. The T-piece also has two passages *c* and *d*, the former being a steam or supply passage and the latter the return. On one branch of the T-piece another T-piece, *f*, is connected, to which the supply and return pipe, *g*, for one set of radiators is connected. A connection, *h*, of the form shown, is connected to the third branch of the T-piece, *e*.

The supply and return pipe, *g*, is led up through successive floors to the radiators, *i*, situated on these various floors.

At the base or just below the first floor, *k*, of the vertical supply and return pipe, *g*, an elbow, *l*, is fitted. The connections from this supply and return pipe, *g*, to the radiators, *i*, may be made by means of I-pieces, accordingly as there are radiators on one or on both sides of the supply and return pipe. In Fig. 1, the first radiator is shown as connected by a T-piece, *m*, it being directly connected to the automatic controlling valve, *n*, on the radiator by means of an elbow, *o*, having two passages therein. The connection for the next pair of radiators is shown in Fig. 1 at *p*. The automatic controlling valve, *n*, is illustrated in detail in Figs. 4-6. In all the various figures the steam passage is indicated by *c*, and the return passage for water of condensation by *d*. That is to say—steam from the single steam pipe, *a*, enters the steam passage, *c*, of the connection *b*, and thence passes by the passages, *c*, of all the piping connected thereto through the automatic valve, *n*, of each radiator, the water of condensation from the latter returning by the passage, *d*, of the supply and return pipe, *g*, and the corresponding passage in the main to the passage, *d*, of the connection, *h*, from which it can be led away through a pipe, *q*, to any desired position. In order to drain the steam passage, *c*, of the supply and return pipe, *g*, of any water of condensation which may accumulate therein, the elbow, *l*, is provided with a small outlet orifice controlled by a regulating screw, *s*, the area of the opening being regulated by the screw so as to allow the water of condensation to dribble out as it tends to accumulate. The screw, *s*, may be substituted by a small thermostatic valve which will automatically open the orifice when water of condensation collects, but close when steam tends to escape therefrom. A similar arrangement is provided on the connections, *e h*, in order to drain water of condensation from the steam passage, *c*, in the steam main.

It will be understood that in the T-pieces, as at *m*, Fig. 1, suitable passages are provided to connect the return passages, *d*, in the branches to the corresponding passages in the body of the fitting, and similar passages may be employed in the fourway-pieces as at *p*, Fig. 1, to connect the steam passages *c* in the opposite branches of the fitting.

In such fittings as are shown in Fig. 2, at *l*, a small extension *v*, is provided to which the drain pipe can be connected.

The automatic controlling valve which is illustrated in detail in Figs. 4-6 is of a similar nature to that described in my prior patent No. 829685, that is to say, the steam valve *w* is mounted upon an iron rod *x*, which is connected at one end by a cap *y* to a copper tube *z*, the opposite end of which is connected to the casing of the valve. Thus the two parts *x* and *z*, being of materials having different coefficients of expansion, will cause the valve *w* to move to or from its seat, accordingly as the temperature in the radiator rises or falls. The valve *w* is screwed upon the rod *x*, and can be rotated in order to allow for setting or adjustment by means of a hand-wheel or lever *2* and a spindle *3*, fitted with a cross-pin *5* adapted to engage ears *6* upon the valve *w*. The screwed boss *24* is screwed into a plug *27* fitting in the radiator *i*. Steam first enters the valve in a chamber *7*, passes the valve *w* when the latter is open 25 into a chamber *8*, and thence, past another valve *9*, into a chamber *10* which leads to the radiator as indicated by the arrows *25*, Fig. 4. The valve *9* is provided with a quick-threaded spindle *11*, in order that it may be 30 thrust down on its seat, or open to the full extent by a small movement of the handle *12*. This valve *9* is not intended as a regulator, but simply to enable the radiator to be shut off when required, the valve *w* effecting 35 the regulation of the steam according to requirements, and effecting this regulation automatically.

The water of condensation in the radiator escapes therefrom as indicated by the arrows *26*, Fig. 4, passing through an opening *13* in the tube *z*, this opening being preferably in the end of the tube *z* remote from the steam inlet. The interior of the tube *z* communicates with an outlet passage *14* in the 45 valve casing through a small opening *15* in one of the plugs or glands *16*, through which the iron rod *x* passes, and which act as a stuffing-box. The opening *15* in the plug *16* referred to is clearly illustrated in detail in 50 Fig. 6.

In order to prevent the plug *16* rotating when once it is put in position, the end of the tube *z* has a small projection *17*, adapted to engage in the opening *15*. Connection from 55 the flow and return pipe to the automatic valve can be made by an elbow *o*, as shown in Fig. 1, the elbow *o* being screwed direct onto the screwed branch *18*, or onto a union *19*, which has a conical nose *20*, adapted to 60 seat in a conical recess in the branch *18*. The elbow *o* or the union *19* has a steam passage *c*, and an outlet or return passage *d*. In order that these two passages may be kept 65 separate, the elbow, or the union, as the case may be, is provided with a partition *21*,

which is extended so as to enter a recess *22* in a partition *23* which divides the inlet passage *7* from the outlet passage *14* in the valve casing. The recess *22* may contain rubber or other packing, if desired.

It is to be understood that, although the invention is especially applicable to steam-heating systems, it is also applicable to hot-water systems wherein the flow and return water is to be kept separate, but wherein 75 only one set of piping is to be used—that is to say, the invention is applicable to any divided-pipe heating system.

Having now described my invention, what I claim as new and desire to secure by Letters Patent is:

1. The combination with a radiator of an automatic regulating valve adapted to permit the inflow of steam and outflow of water of condensation to and from the radiator respectively through a single connection, and comprising a casing having a steam inlet passage *7* therein communicating with a steam outlet passage *14* leading to the radiator, a valve *w* controlling the passage *7* thermostatic means for controlling said valve, comprising an iron rod *x* and a copper tube *z*, having opening *13* therein, glands *16* for packing said iron rod, one of said glands having a passage *15* and said 90 casing having an outlet passage *14*, said passages communicating and leading off the water of condensation, substantially as, and for the purpose, hereinbefore set forth.

2. The combination with a radiator of an 100 automatic regulating valve adapted to permit the inflow of steam and outflow of water of condensation to and from the radiator respectively through a single connection, and comprising a casing, having a steam inlet 105 passage *7* in said casing, and a steam outlet passage *10* leading to the radiator, and a passage *8* connecting the aforesaid passages *7* and *10*, a valve *w* for controlling the communication between the passages *7* and *8*, 110 thermostatic means for controlling said valve, comprising an iron rod *x* and a copper tube *z*, having an opening *13*, glands *16* for packing said iron rod one of said glands having a passage *15* therein; a second valve 115 *9* for controlling the communication between the steam passages *8* and *10*, a quick-threaded spindle *11*, secured to said valve *9*, a handle *12* on said spindle, said casing having an outlet passage *14* therein which is 120 connected to the tube *z* by the passage *14* for leading away the condensed water.

In testimony whereof I have signed my name to this specification in the presence of two subscribing witnesses:

ROBERT ERNEST ATKINSON.
